FOLDABLE STEPLADDER

George H. Stogner, Moultrieville, S. C.

Application September 3, 1936, Serial No. 99,291

2 Claims. (Cl. 228—37)

This invention relates to improvements in folding stepladders and more particularly to that type of folding stepladder having hinged sectional steps which permit the uprights of the ladder to be folded inwardly toward one another.

An object of the present invention is to improve generally upon the type of stepladder mentioned and the invention together with its objects and advantages will be best understood from a study of the following description taken in connection with the accompanying drawings wherein:—

Figure 1 is a front elevational view of a stepladder embodying the features of the present invention, the ladder being shown in extended position.

Figure 2 is a front elevational view of the ladder in folded position.

Figure 3 is an enlarged detail view of the legs and folding brace therefor.

Figure 4 is an enlarged sectional view through one of the steps and the side rails of the ladder with the step in fully extended position.

Figure 5 is an enlarged detail sectional view through a step in partially folded position.

Figure 6 is a fragmentary detail view partly in section and partly in elevation showing the hinge connection between a step section and one of the side rails of the ladder.

Figure 7 is a fragmentary detail view taken substantially at right angles to Figure 6 and

Figure 8 is a fragmentary elevational view of one of the side rails and step viewed from the inner side thereof.

Referring more in detail to the drawings, it will be seen that in the preferred embodiment thereof the improved stepladder comprises a pair of sides or rails 5—5, properly spaced apart, and connected by steps as shown.

The sides 5 have associated therewith supporting legs 6 which are hingedly associated with the sides at the upper ends thereof as at 1. (See Figure 8.)

Each leg 6 has pivoted thereto as at 10 one end of a brace member 9, the other end of which brace member is hinged as at 8 to a section 18 of the upper step 17 of the ladder and as will be clear from a study of Figures 1 and 8. Brace members 9 will thus serve to transmit movement of the step sections to the supporting legs 6 incidental to a folding or unfolding of the ladder so that these legs 6 will extend or fold in a somewhat automatic manner and without requiring the use of the hands for extending or folding

the legs 6 relative to the remaining part of the ladder.

Adjacent the lower ends thereof the legs 6 are connected together through the medium of a foldable brace, which latter, as shown in Figure 5, comprises a pair of sections 12, 13, pivotally connected together as at 14 and respectively pivoted at one end to a leg 6 as at 15. At the hinge joint 14 therebetween one of the brace sections, in the present instance the brace section 12 is provided with an offset longitudinally extended lip or projection 16 which engages the adjacent end of the section 13 when the brace is in fully extended position, the projection 16 thus acting as a stop for limiting the movement of the sections 12, 13 to extended position.

The steps of the ladder, with the exception of the uppermost step, are indicated by the reference numeral 16, the uppermost step being indicated by the reference numeral 17.

Each of the steps 16, 17 comprises a pair of sections 18—18. Each of the sections 18 is substantially channel-shaped in cross section and the outer ends of the sections of steps 16 are pivoted to the sides 5 as indicated generally at 19 while the outer ends of the sections of step 17 are pivoted to the upper ends of the sides 5 as indicated generally at 20. The outer ends of the sections 18 of step 17 are laterally reduced 30 so as to be accommodated in notches 21 provided therefor in the upper ends of the sides as suggested clearly in Figure 8.

Each of the hinges 19 includes a pair of substantially inverted L-shaped brackets or plates 35 22 set in the outer edges of the sides 5 and secured to the sides by screws or other fastening elements with the lateral arms of the plates or brackets projecting inwardly to accommodate therebetween an adjacent end of a step section 40 18 as shown in Figure 6. Said arms of the bracket plates 22 are suitably apertured, and each step section 18 has the side flanges thereof suitably apertured to accommodate a hinge bolt 19 as also will be clear from a study of Figure 6.

Also each step section 18 at the end thereof hinged to a side 5 is, as clearly shown in Figure 7, pressed upwardly as at 18a in a manner to accommodate the hinge bolt to the end that when in extended position the sections 18 of the steps 50 will be in a proper plane, while at the same time, when the latter is in the folded condition shown in Figure 2 the sections 18 of the respective steps will so fold relative to one another as to lie in planes truly perpendicular and consequently will 55

not project outwardly from between the sides 5 of the ladder. In other words, provision is made to insure against any parts of the ladder projecting therefrom when the ladder is folded to the end that, when in folded condition, the ladder 5 may be stored within a comparatively small space.

To facilitate the folding and unfolding of the steps there is provided at the rear side of the 10 ladder a vertically disposed bar 23 through the medium of which and the pins or bolts 24 which connect the sections 18 of the respective steps together, the steps 16 and 17 are connected together so that said steps can be folded or extended in unison.

In connection with the above it will be understood that the sections 18 of the respective steps at their inner ends are hingedly connected together through the medium of hinge bolts 24, 20 and at said hinge connections one section 18 of each step is suitably downwardly offset as at 25 to provide a seat for the adjacent end 26 of the associated step section 18 whereby provision is made for limiting the movement of the sections 25 18 to extended position and to provide for the sections of the steps a joint which will be smooth, neat and will present no projection which might tend to trip the user of the ladder.

It is thought that a clear understanding of the 30 construction, utility and advantages of a ladder of this character will be had without a more detailed description.

Having thus described the invention what is claimed as new is:—

1. A stepladder including spaced side members, steps, each including pivotally connected sections pivoted at their outer ends to the side members 5 and adapted to be folded in parallelism between the side members, a bar connecting all of said steps for folding said steps in unison, supporting legs for said side members, hinges connecting the supporting legs to the side members at the 10 upper ends of the latter, and braces pivoted at one end to the supporting legs and at a second end to the sections of the uppermost step for transmitting movement of the sections of said step to said supporting legs. 15

2. A stepladder including spaced side members, steps, each including pivotally connected sections pivoted at their outer ends to the side members and adapted to be folded in parallelism between the side members, a bar connecting all of said 20 steps for folding said steps in unison, supporting legs for said side members, hinges connecting the supporting legs to the side members at the upper ends of the latter, and braces pivoted at one end to the supporting legs and at a second end to the 25 sections of the uppermost step for transmitting movement of the sections of said step to said supporting legs, and a brace for the supporting legs comprising a pair of pivotally connected sections pivoted at one end to said legs. 30

GEORGE H. STOGNER.
